UNITED STATES PATENT OFFICE.

FRANK W. PERRY, OF DENVER, COLORADO.

METAL SIGN.

No. 884,951.

Specification of Letters Patent.

Patented April 14, 1908.

Application filed July 15, 1907. Serial No. 383,770.

To all whom it may concern:

Be it known that I, FRANK W. PERRY, a citizen of the United States, residing at the city and county of Denver and State of Colorado, have invented certain new and useful Improvements in Metal Signs; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to improvements in metal signs. In my improved construction, I employ a metal frame to which are detachably secured sheet metal panels forming the advertising surface. My improvement is adapted for use, wherever signs are needed. The frame work may be securely anchored whereby it is made stationary. The sheet metal panels may be secured by means of screws, bolts or other suitable fastening devices. Whenever it is desired to change the advertising matter, the panels may be removed, and taken to some convenient place for the purpose. As shown in the drawing, the frame work of the structure 20 is composed of angle iron bars, the body of the frame being rectangular in shape and the sheet metal panels being formed with flanges adapted to pass between the corresponding flanges of two angle iron bars. 25 The flanges of the panels as well as those of the bars are provided with registering openings through which fastening devices may be passed.

Having briefly outlined my improved construction as well as the function it is intended to perform, I will proceed to describe the same in detail reference being made to the accompanying drawing in which is illustrated an embodiment thereof.

40 In this drawing, Figure 1 is a perspective view of a sign in which my improvement is embodied. Fig. 2 is a side elevation of the same. Fig. 3 is an enlarged view showing a spiral leg belonging to the frame work, the same being anchored in cement or concrete. In this view the parts are shown on a greatly 45 enlarged scale. Fig. 4 is a fragmentary detail view. Fig. 5 is a rear view of the sign, the anchored legs being broken off. Fig. 6

is a section taken on the line 6--6 Fig. 5. Fig. 7 is a perspective detail view of one of the detachable metal panels.

The same reference characters indicate the same parts in all the views.

Let the numeral 5 designate vertically disposed angle bars which are arranged in pairs and between which are passed the vertically disposed flanges 6 of a metal panel 7. The flange of the panel is clamped between the adjacent flanges of the angle bars 6 by means of screws 8 or other suitable fastening devices. The panels 7 are also provided with top and bottom flanges 6^A, which are clamped between the horizontal flanges of top and bottom angle bars 5^A, and pieces of strap iron 9 also located at the top and bottom of the sign and having end members 10 bent at right angles to the members 9. One of the vertically disposed angle bars 5 of each pair, is provided with end extensions 12 and 12^A located at the top and bottom respectively. These bottom end extensions as shown in the drawing are provided with spirally shaped legs 13 which are connected with the bottom extensions 12^A of the said angle bars by means of screws 14 or other suitable fastening devices, whereby the said legs may be adjusted to occupy an alined position or any desired angle with the said bars. As shown in the drawing the members 13 are in alinement with the bars and when the frame is erected, the said legs are shown embedded or anchored in concrete or cement 15, holes being formed in the ground and filled with the said substance. The other angle bar 5 of each pair joins the transverse angle bar at the top and bottom as indicated by the line 16, the abutting extremities of the angle bars being beveled for the purpose.

95 The top extensions 12 of the angle bars, coöperate with the parts 10 of the strap iron members 9, to hold narrow top plates 17 in place. The extremities of these top plates are bent at right angles to form end flanges 18 which are clasped between the strap iron parts 10 and one flange of each angle bar extension 12, the said parts being connected together by screws 19 or other suitable fastening devices. The top plates 17 are 100 designed to indicate distances, where these signs are used along railroad tracks. This 105 feature may of course be dispensed with if

desired. The sign is further supported and braced by inclined brace bars 20 located in the rear. As shown in the drawing two of these bars 20 are connected with each pair of angle bars 5 at points 21. The upper bar 20 of each pair of inclined brace bars, is of course the longer. As shown in the drawing each of these inclined bars is provided with a spirally shaped leg 22 which is set into the ground and anchored in concrete as shown in Fig. 3 and also in the same manner as the spiral leg 13 shown in Fig. 1. The brace bars 20 of each pair, are connected as shown at 23 by a horizontally disposed angle bar 24 one extremity of which is connected with the angle bars 5 as shown at 25. The horizontal flange of the angle bar 24, is separated from the vertical flange and turned up against the angle bars 5 as shewn at 26. This feature gives some additional support to the structure. The inner extremities of the vertical flanges of the top and bottom angle bars 5^A, are cut away as shown at 5^B, to make room for one flange of the adjacent angle bar 5 provided with the top and bottom extensions 12 and 12^A.

From the foregoing explanation the use of my improved sign will be readily understood and need not be explained further in detail.

While my improved construction is shown as made of angle bars, the shape of the bars is immaterial and it is evident that flat or other shaped bars may be employed for the purpose without departing from the spirit of the invention.

Having thus described my invention, what I claim is:

1. A metal sign consisting of a frame composed of angle bars, and advertising panels provided with flanges secured between the angle bars by the use of suitable fastening devices whereby the said panels are readily attachable and detachable, substantially as described.

2. A metal sign comprising a frame whose body portion is rectangular in shape and composed of pairs of angle bars, and an advertising panel having flanges formed thereon and clamped between the adjacent flanges

of the angle bars composing the frame, substantially as described.

3. A metal sign composed of a frame formed of pairs of angle bars, one angle bar of each pair having bottom extensions for anchoring purposes, and an advertising panel having flanges clamped between the adjacent flanges of the frame angle bars, substantially as described.

4. A metal sign consisting of a frame composed of bars, and advertising panels provided with flanges secured to the bars by the use of suitable fastening devices, whereby the said panels are readily attachable and detachable, substantially as described. 65

5. A metal sign having a frame work whose body portion is rectangular in shape and composed of horizontally and vertically disposed pairs of angle bars, panels provided with flanges passed between the angle bars of the frame, suitable means for clamping the bars together upon the flanges of the panels, one bar of each vertically disposed pair being provided with anchoring extensions, and suitable means for bracing and supporting the sign from the rear, substantially as described. 70

6. A metal sign consisting of a frame, advertising panels detachably connected with the frame, pairs of inclined supporting bars connected with the frame in the rear, the individual inclined member of each pair being arranged one above the other, their lower extremities having anchoring extensions, and horizontal members connecting each pair of inclined brace bars with each other and with the frame of the sign, substantially as described. 80

7. A metal sign having a frame composed of pairs of horizontally and vertically disposed bars, and a panel provided with a flange detachably clamped between the pairs of bars composing the frame, substantially as described. 85

In testimony whereof I affix my signature in presence of two witnesses.

FRANK W. PERRY.
